UNITED STATES PATENT OFFICE.

CHARLES B. LEE, OF GALVESTON, TEXAS.

REFRIGERATING-MACHINE.

SPECIFICATION forming part of Letters Patent No. 292,925, dated February 5, 1884.

Application filed October 22, 1883. (No model.)

To all whom it may concern:

Be it known that I, CHARLES B. LEE, of Galveston, in the county of Galveston and State of Texas, have invented a new and useful Improvement in Refrigerating-Machines; and I do hereby declare the following to be a full, clear, and exact description thereof, reference being had to the accompanying drawings, making a part of this specification, in which—

Figure 1 is a longitudinal vertical section of my improved refrigerator. Fig. 2 is a plan view of the refrigerator and of the cold-air-distributing box, the covers of the same being removed. Fig. 3 is an elevation of the fan and influent pipes, partly in section; and Fig. 4 is an enlarged view, showing more plainly the construction of the refrigerator-box.

Like letters of reference indicate like parts in each.

My invention relates to the refrigeration of air; and it consists of a box of wood or metal having in it a series of pipes arranged longitudinally in manifold, and extending across it laterally a series of transverse partitions, which run alternately from opposite sides, said box having a detachable top and hinged sides, whereby access may be had to the refrigerating-pipes for repairing and for like purposes.

It also consists in the manner of attaching the manifold pipes by means of flanges at both ends to connecting-pipes.

It also consists in a perforated cold-air-distributing box placed in the lower part of the room, and a perforated air trunk or box in the upper part of the room, combined with a suction-fan for withdrawing air from the upper part of the room and forcing it through the refrigerating-box before mentioned to cool it, and through the cold-air-distributing box into the room.

It also consists of a valve arranged in the influent opening of the suction-fan, in combination with a pipe leading from the air-trunk in the top of the room, and with a pipe leading in from the outer air, in such a manner that by shifting the valve the air which is to be refrigerated may be taken either from the room or from the outside.

To enable others skilled in the art to make

and use my invention, I will now describe its construction.

The refrigerating chamber or box is indicated at *a*. It has a removable top secured to the sides by keys *a'*, and hinged sides, as indicated at *a''*, so that the internal construction may be gotten at for the purpose of repairs. Inside of this box are two or more series of pipes, *b*, arranged longitudinally in vertical series of two or more, as may be desired, and the pipes of each series are attached at each end to a connecting-pipe, *d*, common to the series, by means of a separate flange, *d'*, so that in case of any accident to the pipe, or in case it is desired to reduce the number of pipes in the chamber, any one or more pipes may be taken off by simply unscrewing the bolts *d''* and taking off the flange *d'*, without displacing or removing other pipes. The openings thus made in the connecting-pipes *d* may be closed by placing a blind or solid flange over them.

Arranged at suitable intervals, and extending alternately from opposite sides of the chamber *a*, are transverse partitions *c*, through which the pipes *b* pass. The purpose of the partitions is to cause the air to have a longer run in the refrigerator and to pass over a greater amount of refrigerating-surfaces. The partitions may be arranged as closely as desired or is necessary to produce any required degree of temperature. The same may also be said with reference to the number of pipes *b* which are placed in the box. The refrigerator is supplied to the pipes *b* through the pipes *o*, connected by flanges *o'*. This refrigerant may be ammonia or similar gas, or any non-congealable liquid. The air is supplied to the chamber *a* by means of a suction-fan, *h*, operated by a belt and pulley, *k*, the air being drawn in at the influent opening *i* and driven through the pipe *g* into and through the chamber *a*, whence it is discharged through the air-trunk *l* into the distributing-chamber *m*, whence it passes through the perforations *n* into any desired part of the room. The air to be refrigerated may either be drawn from the top of the room by the use of a perforated box or air-trunk, *e*, similar to the air-trunk *m*, or, in case it is desired to inject fresh air into the

room, through a pipe, *p*, from the outside. In the influent opening *i*, I arrange a valve, *q*, by means of which I am enabled to close the pipe *p* or the air-trunk leading from the room, 5 so as to draw my supply from either at will. I prefer to distribute the cold air in the lower part of the room and take the supply from the upper part, so as to cause the exhaustion of the warm air and a continuous circulation 10 through the room. The moisture from the air is deposited upon the pipes *b* in the form of frost in the box *a*. When it collects so thickly as to interfere with the operation of the refrigerator, it may be melted out by forcing 15 warm air through the pipes. It is then drawn off through a waste-pipe, *r*. By this means I prevent the collection of frost in the room, which, in case of stoppage of the machine, would thaw off and create a dampness.

20 In case of a stoppage of the machine the room should be closed, and then the air will remain perfectly dry and cold for a considerable length of time.

The advantages of my machine are simplicity of construction, ease of making repairs, 25 ability to make repairs without stopping its operation, ability to obtain any required degree of cold, and the dryness and perfect refrigeration of the air which are obtained thereby.

30 What I claim as my invention, and desire to secure by Letter's Patent, is—

1. A refrigerating-box having a detachable top and hinged sides, a series of pipes 35 for containing the refrigerant, arranged within said box, and a series of partitions extending alternately from opposite sides nearly

across the box, for causing the air to be cooled to make a long circuit in passing through the box, substantially as and for the purposes described. 40

2. A refrigerator - box having a series of refrigerant - pipes extending longitudinally through it, each pipe being connected at each end with a connecting-pipe by means of separate flanges, and the end pipes connected by flanges with supply and discharge pipes, whereby any one or more of the pipes may be taken out or replaced without interfering with the operation of the machine, substantially as and 45 for the purposes described. 50

3. In combination with a refrigerator, a perforated cold-air-distributing box in the lower part of the room, a perforated air-box in the upper part of the room, and suction-fan for 55 withdrawing the warm air from the room and forcing it through the refrigerator and the cold-air box and out into the room, substantially as and for the purposes described.

4. The suction-fan having a valve, and arranged in connection with a fresh-air pipe, and a pipe leading from the upper part of the room, in combination with a refrigerator and an air-distributing box, whereby the air may be drawn from the outside or from the room 65 at will, substantially as and for the purposes described.

In testimony whereof I have hereunto set my hand this 29th day of September, A. D. 1883.

CHARLES B. LEE.
